BUFFING MACHINE

Martin H. Stevens, Youngstown, Ohio

Application April 9, 1940, Serial No. 328,660

2 Claims. (Cl. 15—102)

This invention relates to a buffing machine and more particularly to a buffing machine adapted for cleaning and polishing trays and flatwork.

The principal object of the invention is the provision of a buffing machine particularly adapted for cleaning composition trays such as are commonly used in cafeterias and the like.

A further object of the invention is the provision of a tray cleaning machine incorporating mechanism for simultaneously moving and buffing the trays being cleaned.

A still further object of the invention is the provision of a tray cleaning machine incorporating separate means for cleaning the rounded corners of the trays.

Specifically, the buffing machine shown and described herein has been designed for removing oxidation, grease, dirt and other accumulation from trays commonly used in cafeterias which are ordinarily formed of hard rubber, plastics, formica and the like wherein as much as one thirty-second of an inch of oxidation and dirt accumulation is commonly found to exist.

While the various cafeteria operators have commonly attempted to clean such trays with various cleaning solutions and alkalies and acids, the uniform result has been an unsatisfactorily cleaned tray as there has been no cleaning equipment available capable of removing the oxidation and dirt accumulations commonly found. The buffing machine shown and described herein cleans and refinishes the trays leaving a mirrorlike finish.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a top plan view of the buffing machine.

Figure 2 is a side elevation of the buffing machine showing in detail the driving arrangement employed.

Figure 3 is an enlarged detail view of a portion of the buffing machine shown in Figures 1 and 2 and shows in detail the buffing apparatus

utilized in cleaning the rounded corners of the trays.

By referring to the drawing and Figures 1 and 2 in particular it will be seen that the buffing machine comprises a rectangular frame 10 preferably formed of metal and welded, the uppermost portion 11 of which is provided with two pairs of rail like cross members 12 adapted to support tray carrying tables 13 and 14 slidably positioned thereon. By referring to Figure 1 of the drawing it will be seen that these rail like cross members 12 are preferably formed in an inverted V shape so that guides positioned on the bottom of the movable tables 13 and 14 will insure the accurate alignment of the tables 13 and 14 thereon. In order that trays positioned on these tables 13 and 14 against transversely positioned rails formed at the back of each, may be suitably cleaned, buffer assemblies comprising a plurality of cloth buffing disks 15 and 16 have been rotatably positioned above each of the tables 13 and 14 by means of frames each of which comprises a pair of cross members 17 and a pair of arms 18, the arms being pivoted at the back to upwardly extending portions of the frame 10 and carrying the buffing assemblies 15 and 16 between their outermost ends on shafts 19 and 20. These frames carrying as they do the buffing wheel assemblies are normally positioned by spring means slightly above the surfaces of the tables 13 and 14. Suitable linkage 21 connected to foot pedals 22 is provided as a means of moving the buffing assemblies downwardly upon the surface of trays being cleaned. It will be seen that proper rotation of these buffing assemblies 15 and 16 will serve to hold the trays in position on the tables 13 and 14 against the transverse rail formed at the back of each. In order that the trays on the tables 13 and 14 will be adequately cleaned, reciprocating movement is imparted these tables 13 and 14 by means of rocker arms 23 and 24 which in turn receive motion from crank members 25 and 26. The rocker arms 23 and 24 impart reciprocating movement to the tables 13 and 14 by way of horizontal L shaped members 23A and 24A to which they are pivoted at one end, the opposite ends of the members 23A and 24A are pivoted to the undersides of the tables 13 and 14 respectively. The crank members 25 and 26 are formed in connection with the driving means which comprise a plurality of shafts 27 positioned transversely of the frame 10 and carried in suitable bearings by cross members thereof. In order that driving motion imparted the principal

drive shaft 28 by a motor 29 may be suitably reduced and imparted to the shaft 27 carrying the crank members 25 and 26, a plurality of large and small sheaves 30 and 31 respectively are belted together as shown in Figure 2 so that driving motion imparted the shaft 27 carrying the crank members 25 and 26 will be approximately forty-three revolutions per minute.

In connection with the driving means it will be observed that a belt 32 conveys motion from the principal drive shaft 28 to one of the large sheaves 30 on one of the shafts 27 and that a belt 33 conveys motion from a small sheave 31 of this same shaft to a large sheave on another of the shafts 27. Still another belt 34 conveys the motion of this latter shaft 27 from a small sheave 31 thereon to a large sheave 30 on the lowermost shaft as shown in Figure 2. The crank members 25 and 26 are positioned on this lowermost shaft 27 and impart their reciprocating movement to the rocker arms 23 and 24 by means of slots formed thereon by guides positioned thereon. It will thus be seen that when the motor 29 is energized the principal shaft 28 revolves and causes the tables 13 and 14 to move with a reciprocating movement. It will further be seen by referring to Figures 1 and 2 of the drawing that sheaves 35 and 36 carry belts 37 which serve to drive the buffer assemblies 15 and 16 by means of their shafts 19 and 20. By referring again to Figure 1 it will be seen that the principal shaft 28 is mounted in tubular housings 38 which are in turn affixed to upright extensions of the frame 10 as shown in Figure 2. It will thus be seen that a tray placed first upon the table 13 is cleaned lengthwise with the exception of the ends which, due to the round corner formation of the trays, makes this portion of the tray impossible to reach. The tray is subsequently removed from the table 13 and placed sideways on the table 14 where the two uncleared end sections of the trays are cleaned by the buffers 16. The tray when removed from the table 14 has been cleaned with the exception of small areas in each of the rounded corners. In order that these small areas adjacent the rounded corners of the trays may be cleaned, a secondary buffer is necessary and is provided as shown in detail in Figure 3 of the drawing. By referring to this figure it will be seen that a bracket 39 has been positioned on an upwardly extended portion of the frame 10 and carries in a vertical manner through arms formed thereon, a shaft 40 the lower end of which is provided with a buffer 41 which directly opposes a small table 42 upon which the corners of the trays may be positioned and cleaned. A compression spring 43 normally holds the buffer 41 in

elevated relation to the table 42 and linkage 44 connecting with a foot pedal 45 provides means for manually lowering the buffer upon the tray to be cleaned. In order that this buffer may be rotated a sheave 46 is positioned immediately above the coil spring on the shaft 40 and, as may be seen in Figures 1 or 2, it is connected by means of a belt to a sheave 47 positioned on one end of the drive shaft 38.

It will thus be seen that a buffing machine capable of cleaning a complete tray has been designed wherein trays are subjected to reciprocating movement while being buffed by rotating buffers and, further, that the various corner portions of the trays may be conveniently cleaned by subjecting them to the secondary buffing means formed as part of the buffing machine.

What I claim is:

1. A device of the class described comprising a frame, guide members positioned across the top of the said frame, movable tables positioned on the said guide members, rocker arms positioned in the said frame adapted to impart reciprocating movement to the said tables, a plurality of shafts positioned in the said frame, belts interconnecting the said shafts by means of sheaves positioned thereon so as to impart movement to the said rocker arms through cranks carried on one of the said shafts, a drive shaft positioned adjacent the top of the said frame and adapted to drive the said shafts, together with buffer assemblies positioned on secondary frame means above the said reciprocating tables, the said drive shaft adapted to drive the said buffer assemblies and means for moving the said buffer assemblies into and out of relation with work positioned on the said tables substantially as described.

2. In a buffing machine adapted for cleaning and polishing trays and flatwork and comprising a frame having guide members positioned across the top thereof, tables movable longitudinally of said frame positioned on said guide members and means for imparting reciprocating movement to the said tables comprising rocker arms positioned in the said frame, a shaft positioned in the said frame, cranks formed in said shaft and cooperating with the said rocker arms so that movement imparted the said shaft will result in the reciprocating movement of the said tables, buffer assemblies positioned above the said tables and movable vertically in relation thereto, means for rotating the said buffer assemblies and said shaft together with means for moving the said buffer assemblies into and out of relation with work positioned on the said tables.

MARTIN H. STEVENS.
